UNITED STATES PATENT OFFICE.

WESLEY A. PETREE, OF MIZPAH, NORTH CAROLINA.

TOBACCO-HANGER.

SPECIFICATION forming part of Letters Patent No. 425,548, dated April 15, 1890.

Application filed November 4, 1889. Serial No. 329,173. (No model.)

To all whom it may concern:

Be it known that I, WESLEY A. PETREE, a citizen of the United States, residing at Mizpah, in the county of Stokes and State of North Carolina, have invented certain new and useful Improvements in Tobacco-Hangers; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to a novel and useful device for stringing tobacco-leaves for the purpose of drying the same; and the nature of my invention consists in a tobacco-leaf-stringing device, which will be fully understood from the following description, taken in connection with the annexed drawings, in which—

Figure 1 is a perspective view of the improved stick or hanger having the inverted bow spring wire attached to it, showing several leaves strung upon it. Fig. 2 is a sectional perspective view, in detail, of the stick enlarged, showing the two ends of the stick and the hooked ends of the wire. Fig. 3 is a view of the wire hook. Fig. 4 is a longitudinal section of the device.

Similar letters of reference indicate corresponding parts in the several figures.

Referring to the annexed drawings by letters, A designates a stick of any suitable length, which is adapted to be hung upon rack-bars in a drying-house. This stick may be rectangular in cross-section, or it may be of any other suitable shape. It is perforated at a b. These perforations are preferably elongated and terminate in <-shaped slots a' b', for a purpose hereinafter explained.

In practice I prefer to employ sticks which are produced at the saw-mill without dressing, and to form the perforations, as described, by augers and indentations, although I do not confine myself to any mechanical means for

producing the said holes and indentations or elongated recesses.

B designates my improved bowed needle, which I use in combination with the perforated stick above described. This needle serves a double purpose, to wit: It is constructed of any suitable gage of wire and of a length adapted to be sprung into the perforations a b of the stick A. On one end of this needle is formed a hook d, adapted to engage with the perforation a and to enter the slot a' thereof. The opposite end of the needle is provided with a pointed hook d', which is adapted to engage with the perforation b and to enter the slot b' thereof. The needle itself is bow-shaped and made of spring-wire, so that not only by its own elasticity do its hooks hold themselves in the perforations made in the supporting-stick, but it will be observed that the weight of the tobacco-leaves which I string upon it will also draw the hooks more firmly into the grooves above described.

Now in operating this device the pointed hooked end of the needle is held free from the stick, the opposite end of the needle being engaged with the stick and the latter adjusted upon a table against a suitable stop. The leaves are then strung upon the needle and properly adjusted thereon, as many as may be desired. When the needle is filled, the pointed hooked end is engaged with the perforation in the stick A and the stick hung upon a rack in the drying-house.

Having described my invention, what I claim, and desire to secure by Letters Patent, is—

The within-described improved article of manufacture, consisting of a tobacco-stick having the perforations a b through it, in combination with a removable spring bow needle B, bent and pointed at its ends, as specified.

In testimony whereof I affix my signature in presence of two witnesses.

WESLEY A. PETREE.
